UNITED STATES PATENT OFFICE.

FRANK A. SNIDEMAN, OF SOUTH HAVEN, MICHIGAN.

OIL-BURNER ATTACHMENT FOR WOOD OR COAL STOVES.

1,205,043.

Specification of Letters Patent. Patented Nov. 14, 1916.

Application filed March 1, 1916. Serial No. 81,473.

To all whom it may concern:

Be it known that I, FRANK A. SNIDEMAN, a citizen of the United States, residing at South Haven, county of Van Buren, State 5 of Michigan, have invented certain new and useful Improvements in Oil-Burner Attachments for Wood or Coal Stoves, of which the following is a specification.

This invention relates to improvements in 10 oil burner attachments for wood or coal stoves.

The main objects of this invention are: First, to provide an oil burner attachment adapted for wood or coal stoves which is 15 simple and economical to install and is very efficient and also one which is very convenient to use. Second, to provide a structure of the class described which may be quickly converted into a fire starting device when 20 the stove is used as a coal or wood stove.

Further objects, and objects relating to structural details, will definitely appear from the detailed description to follow.

I accomplish the objects of my invention 25 by the devices and means described in the following specification.

The invention is clearly defined and pointed out in the claims.

A structure which is a preferred embodiment 30 of my invention is clearly illustrated in the accompanying drawing, forming a part of this specification, in which:

Figure I is a detail plan view of a cook 35 stove having my improved oil burners installed therein, the stove parts being shown mainly in conventional form and with parts broken away to better show structural details. Fig. II is an enlarged detail view, partially in vertical section, on a line corresponding to line 2—2 of Fig. I. Fig. III 40 is a detail view, partially in vertical section, of a heating stove embodying the features of my invention. Fig. IV is a perspective view of one of my improved oil burners removed from the stove. Fig. V is 45 a similar detail perspective view of one of my improved burners modified as a starting or kindling burner for coal or wood stoves. Fig. VI is a detail vertical section on a line 50 corresponding to line 6—6 of Fig. V.

In the drawing, similar reference characters refer to similar parts throughout the several views, and the sectional views are

taken looking in the direction of the little arrows at the ends of the section lines. 55

Referring to the drawing, 1 represents the top of a cooking stove. 2 one of the side walls thereof. 3 the fire pot, and 4 the grate. These parts are shown mainly in conventional form as the structural details 60 are unimportant, my improvements being adapted for embodiment in a variety of stove structures.

I provide a block-like burner body 5, preferably a casting, having a fuel passage 6 therein to which the supply pipe 7 is connected, the pipe being threaded into the burner body. This pipe leads from the fuel supply tank or reservoir 8, which is supported in a convenient position so as to feed by 70 gravity. The pipe 7 is disposed through the side wall 2 of the stove and fire pot 3. The pipe is controlled by the valve 9, while the flow of fuel or feed is controlled by the needle valve 10. The burner tube 11, in 75 the structure illustrated, consists of a pair of coils disposed vertically side by side and terminating in a tip 12 disposed laterally within and at the bottom of the coils. The tip 12 is provided with a jet orifice 13. The 80 burner tube 11 is provided with a threaded nipple portion 14 threaded into the body member 5 so as to communicate with its passage 6.

I preferably provide a filter 15 which consists of a short section of twisted wire cable disposed within the tube at its inlet end. I find, in practice, that this filter is not likely to clog and at the same time it is very durable and is effective in preventing any substance reaching the burner tip which would 85 be likely to clog the delivery orifice 13 thereof. 90

I preferably provide a circular deflector plate 16 having a projecting ear 17 on its upper side perforated to receive one of the coils, the perforation being of such size that the deflector may be readily adjusted to the desired position on the coil to deflect the flames as, for example, when it is desired to 100 heat an article directly above the burner plate the deflector is adjusted over the jet so as to spread the flame. If it is desired to use the oven for baking purposes the deflector plate may be adjusted to deflect the 105 flames rearwardly toward the oven wall.

- The burner body member 5 is provided with recesses 18 on its upper side adapted to serve as starting cups. These recesses are preferably filled with asbestos, sand or ashes, indicated at 19. In starting the burner the valve 9 is opened long enough to allow a quantity of the oil to flow from the burner tip opening 13 down onto the body member and into the starting cups.
- 10 When a sufficient quantity has been discharged the valve is closed and the oil lighted. This heats the burner tube above so that when the oil, which has been permitted to flow from the orifice, is consumed, 15 the oil may be turned on again and is vaporized in its passage to the discharge orifice 13 so that it issues as a gas. After being started the coils are heated so as to thoroughly vaporize or gasify the fuel.
- 20 My improved burner is very efficient and at the same time is very economical in fuel consumed when compared with the resulting heat units.
- In the structure shown in Fig. I I provide a pair of the burners, arranged one below each lid, the burner body members 5 being connected by a pipe 20 controlled by the valve 21. My improved burner may be placed upon the grate in a cooking or 30 heating stove without packing the grate as is customary in oil burning attachments, that is, it is usual practice to cover the grate with ashes, asbestos, sand or the like. My improved burner, however, does not 35 necessitate this. A further advantage is that fuel is consumed without objectionable deposits of carbon within the fuel place or upon the receptacles heated.
- In the modification shown in Fig. III 40 the burner is placed centrally within the fire pot 22, the pipe 23 being arranged through the wall of the stove substantially as is done when the structure is applied to a cooking stove. When it is desired to use the burner body 5 as a means for kindling or starting a coal or wood fire the burner tube 11 is removed and the nozzle 24 is substituted. This nozzle is a short piece of pipe closed at its upper end and threaded at its lower end 45 to be threaded into said burner body. The nozzle has lateral perforations 25 which constitute jet orifices for the escape of the fuel from the burner tube 24. When it is desired to start a coal fire, for example, the 50 coal is placed in the fire pot directly upon the burner thus modified and the oil is turned on and ignited. The burner may be allowed to burn until the coal is well started when it may be cut off.
- 60 I have illustrated and described my improvements in the form in which I have embodied the same in practice. I have not attempted to illustrate or describe various modifications or adaptations to the different types of stoves, as I believe the dis-

closure made will enable those skilled in the art to which my invention relates to embody or adapt the same as circumstances may require.

Having thus described my invention, 70 what I claim as new and desire to secure by Letters Patent, is:

1. In a structure of the class described, the combination of a block-like burner body member having a fuel passage therein, a 75 burner tube comprising a plurality of coils disposed vertically side by side and terminating in a tip disposed laterally within and at the bottom of the coils and provided with a jet orifice in its top, said tube being provided with a downwardly projecting nipple portion secured to said body member and communicating with said passage thereof, and a section of wire cable disposed at the inlet end of said tube and constituting a 80 filter.
2. In a structure of the class described, the combination of a block-like burner body member having a fuel passage therein, a 85 burner tube comprising a plurality of coils 90 disposed vertically side by side and terminating in a tip disposed laterally within and at the bottom of the coils and provided with a jet orifice in its top, said tube being provided with a downwardly projecting nipple 95 portion secured to said body member and communicating with said passage thereof.
3. The combination with a stove comprising a fire pot and grate, of a block-like burner body member disposed on said grate 100 and having a fuel passage therein and a starting cup recess on its upper side, a burner tube comprising a vertically disposed coil terminating in a tip disposed at the bottom of the coil, said tube being provided 105 with a downwardly projecting nipple portion secured to said body member and communicating with the passage thereof, and a deflector plate having a perforated ear on its upper side engaging said coil whereby said 110 plate is adjustably supported above the tip.
4. The combination with a stove comprising a fire pot and grate, of a block-like burner body member disposed on said grate and having a fuel passage therein and a 115 starting cup recess on its upper side, a burner tube comprising a vertically disposed coil terminating in a tip disposed at the bottom of the coil, said tube being provided with a downwardly projecting nipple portion secured to said body member and communicating with the passage thereof, and a section of wire cable disposed at the inlet 120 end of said tube and constituting a filter.
5. The combination with a stove comprising a fire pot and grate, of a block-like burner body disposed on said grate and having a fuel passage therein and a starting cup recess on its upper side, a burner tube comprising a vertically disposed coil termi- 125 130

nating in a tip disposed at the bottom of the coil, said tube being provided with a downwardly projecting nipple portion threaded into said body member so as to 5 be removable therefrom and communicating with the passage thereof, and a nozzle adapted to be threaded into said body member in lieu of said burner tube.

In witness whereof, I have hereunto set my hand and seal in the presence of two 10 witnesses.
